UNITED STATES PATENT OFFICE.

DAVID C. MEARA, OF TOLEDO, OHIO.

CARBURETER.

1,198,043.

Specification of Letters Patent. Patented Sept. 12, 1916.

Application filed January 22, 1916. Serial No. 73,811.

To all whom it may concern:

Be it known that I, DAVID C. MEARA, a citizen of the United States, and a resident of Toledo, in the county of Lucas and State of Ohio, have invented a certain new and useful Carbureter; and I hereby declare the following to be a full, clear, and exact description of the invention, such as will enable others skilled in the art to which it appertains to make and use the same, reference being had to the accompanying drawings, and to the characters of reference marked thereon, which form a part of this specification.

15 My invention relates to carbureters.

The invention has for its object to provide an efficient regulating means to regulate the suction on the gasoline to produce mixtures of the gasoline and the air.

20 The invention may be contained in many forms of construction usable for different purposes, all of which come within the interview of my claims hereinafter appended.

To show the practicability of my invention I have selected one of such constructions as an example and shall describe it hereinafter. The construction selected is illustrated in the accompanying drawings.

Figure 1 is a vertical sectional view of the 25 carbureter. Fig. 2 is a horizontal sectional view taken on a line 7,7 indicated in Fig. 3. Fig. 3 is a sectional horizontal view taken on line 8,8 indicated in Fig. 3. Fig. 4 is a perspective view of the carbureter choke cylinder. Fig. 5 is a perspective and broken view of an automatic auxiliary air inlet valve.

1. Fig. 1 is the carbureter casing which is composed of the head 2 framing the upper 30 part of the carbureter, the bowl 3 and the air intake or horn 4.

The head 2 is provided with a coupling flange 10 whereby the carbureter may be connected with a manifold leading to the cylinder of the engine. Within the head 2 is mounted a butterfly valve 11. The butterfly valve is located upon a shaft 12 and is keyed thereto by means of the screw 13. The shaft 12 is supported in bearings 14 located in bosses 14 formed in the outer wall of the head 2 of the carbureter. The shaft 12 may extend beyond the boss on either side of the head 2 in order that the lever 15 may be connected to either end of the shaft 12. The lever 15 is provided with a split portion 16 which may be clamped to

the end of the shaft 12 for securing the lever 15 to the shaft 12 at any desired location with reference to the butterfly valve 11 which is keyed to the shaft 12. The lever so arm 15 may be thus located above or below the shaft when the butterfly is at an intermediate position or the lever may be located on either side of the carbureter casing. The lever 15 is also provided with a plurality of 65 holes 17 into which the end of the connecting rod 18 may be inserted for the purpose of operating the carbureter to control the engine to which the carbureter is connected. The plurality of openings 17 provide means 70 for adjusting the lever movements, and consequently the extent of opening of the passageway from the carbureter to the engine by the butterfly valve 11, according to the longitudinal movements of the connecting 75 rod 18.

The butterfly valve 11 is connected at its upper edge to a choke cylinder 25 by means of an adjustable coupling consisting of a flattened rod 26 which threads into the sleeve 27 and the two are secured in their relative position by the pivoted pin 28 by which the rod is connected to the butterfly valve, and by the rod 29 with which the sleeve 27 is connected with the cylinder 25 85 and by the lock nut 30 which is threaded upon the rod 26. The pin 28 provides pivotal movements of the rod 26 relative to the butterfly valve 11 when the valve 11 is turned by the operation of the lever 15. 90 Relative pivotal movement of the coupling is also permitted by the rod 29 which is located in the upper end of the cylinder 25 which is secured to the sleeve 27 by means of the cotter pin 31.

95 The lower end of the sleeve 27 is bifurcated and the forkations extend on opposite sides of the pin 29 which is provided with the flattened portion 32. The pin extends through holes 33 located in the upper 100 end of the cylinder 25. The cylinder 25 is located in a tube 35 which forms an extension of the head 2 and connects with the head 2 by means of the frustulm shaped enlargement 36 which is made integral with the plate 37 forming the bottom of the head part 2 which sits on the bowl 3. It has a seating flange 38 which effectively prevents the escape of gasoline vapors.

The pin 29 is kept in position in the cylinder 25 by the inner surface of the tube 35. The ends of the pin 29 are cylindrical so as

to conform to the shape of the inner surface of the tube 35. The cylinder 25 therefore is adjustably connected with the butter-fly valve 11 which is oscillated on its axis by the lever 15 and the two are operated together.

The inner surface of the cylinder 25 is provided with two surfaces which diverge from the center and which are frustumal in form. The center of the cylinder, when the butter-fly valve 11 is nearly closed, is located substantially at the end of the nozzle 40 which is located on the end of the tube 41.

The tube 41 is threaded into the bottom of the horn 4. The interior of the tube 41 however communicates with a passageway 42 which is formed in the horn 4. The horn 4 is threaded on the lower end of the tube 35. The tube 35 is provided with the flange 43 which clamps the lower end of the bowl 3 about the opening formed in the bottom thereof and also a washer 44 when the horn 4 is secured on the end of the tube 35. Also the head 2 is secured to the top of the bowl 3. The washer 44 may be of different thicknesses to bring the horn 4, when the same is tightly secured on the end of the tube 35, into any desired position relative to the carbureter or relative to the other mechanisms of the engine.

The bowl 3 is maintained partially full of gasoline or other liquid fuel. The gasoline or other hydro-carbon fuel enters the passageway 42 and partially fills the tube 41. Air enters the horn 4 by reason of the suction produced in the operation of the engine, in the manner well known in the art, and passes upward through the carbureter, through the tube 35 and around the tube 41. It passes through the cylinder 25 having the contracted area and thereby brought into contact with the nozzle 40 located on the end of the tube 41. The velocity or rate of movement of the air as it passes the nozzle 40 will depend upon not only the speed of the engine which is largely controlled by the butter-fly valve 11, but also it will be dependent upon the extent of the opening formed by the butter-fly valve 11 and the relative position of the cylinder 25 with reference to the nozzle 40. The inner surface of the cylinder 25, according to its position relative to the nozzle 40 will control the suction upon the gasoline or other liquid hydrocarbon which is fed to the tube 41 from the bowl 3. This will also control the mixture so as to keep it substantially uniform. It also operates to give a richness to the mixture when the engine is running at low speed thereby increasing the power of the engine at that time.

The nozzle 40 is provided with a central pin opening 50 which connects the interior of the tube 41 with the cone shaped recess 51 forming the exit of the nozzle 40. As the gasoline is drawn from the nozzle 41

when the butter-fly valve is still open and the cylinder 25 consequently is drawn to a position such that the contracted area of the cylinder is slightly above the nozzle, the gasoline is sprayed upward and laterally by reason of the shape of the exit 51 producing thereby a thorough mixture of the hydrocarbon and the air.

The nozzle 40 is also provided with a passageway 53 which extends from the interior of the tube 41 or nozzle 40 to the side of the nozzle 40. The nozzle 40 is provided with a conical surface 52 which slightly flares outward toward the edge of the nozzle 40. The air rising around the pipe 41 is brought into intimate contact in its upward movement against the surface 52 and as it passes the opening 51 by reason of its upward movement and its suction it readily draws vapor through the opening 51. This is particularly of value in starting the engine and when the engine is operated at very low speed.

The bowl 3 is provided with upwardly extending fingers or cylindrical sectors 60 which are provided with passageways 61. The cylindrical form of the fingers 60 operates to hold the flange 43 of the tube 35 in position and raises the point of entrance for the hydrocarbon into the passageway 42. The openings 61 being located well above the bottom of the bowl 3 receive a liquid hydrocarbon which is substantially uniform in character. The heavier gasoline settles to the bottom of the bowl 3 and below the upper ends of the passage-way 61 also all sediment will collect around the fingers 60 within the bottom of the bowl 3 and will not enter the passageway 42. The passageways 61 communicate through the openings 62 formed in the washer 44 with a channel 63 located around the opening in the horn 4 in which the tube 35 is threaded. The annular passage-way 63 communicates with the passageway 42 and feeds the gasoline into the passageway 42 which is taken from both sides of the bowl and from above the bottom of the bowl.

The gasoline is fed into the bowl 3 through the pipe 70. Its flow is regulated by means of the needle valve 71 located on the end of a pin 72 which is supported in a suitable housing 73 formed preferably integral with the bowl 3. The needle valve 71 is provided with a seat formed in the plug 74 which is suitably connected with the pipe 70. A cap is threaded into the upper end of the housing 73 and receives the upper end of the pin 72. By means of the plug 74 and the cap 75 the needle valve may be readily assembled and connected with the float 80 which may be made of cork or other suitable buoyant material or formed with an air chamber therein to cause the same to float on the surface of the hydrocarbon

liquid which is received into the bowl 3. The float 80 is pivotally connected to the bowl 3 intermediate the housings 73 and the bowl 3, by means of an arm 81 and pins 82. 5 The outer end of the arm 81 is bifurcated having furcations extending between a pair of flanges 83 formed on the pin 72 for the purpose of raising and lowering the pin 72 to open and close the valve according to the 10 level of the liquid within the bowl in a manner well known in the art.

The mixture of gasoline and the air is not only modified according to the position of the cylinder 25 but also by reason of the 15 suction produced by the engine when running at intermediate speeds or at high speed on one or more auxiliary valves which are automatically opened to the temper mixture which is enriched by the wide opening of 20 the butter-fly valve 11. When the engine runs at a high speed at a moderate opening of the butter-fly valve 11 and when the load on the engine is relatively small one or more auxiliary valves are automatically opened to 25 give more air to the mixture and consequently dilute it.

The head 2 is provided with bosses 90 which extend radially from the axis of the head. Sleeves 91 having heads 92 are pushed 30 with some pressure within the bosses 90. The sleeves 91 are provided with slots 93 in which are located ends of cross-bars 94. The ends of cross-bars 94 terminate in cylindrical surfaces 95 which conform to the inner surfaces of the bosses 90. Pins 96 are connected to the cross-bars 94. Disks 97 move along the pins 96 and are yieldingly held against the heads 92 by means of the springs 98 which are located intermediate 40 to the cross-bars 94 and the disks 97. The springs 98 operate to seat the disks 97 within the head 92. The springs 98 differ in their tension so as to press the disks 97 yieldingly outward with different pressures. By 45 this means when the suctions within the head 2 are produced by various speeds of the engine, one or both of the auxiliary valves or disks will open, as the butter-fly valve is located intermediate to the auxiliary 50 valves and the engine, and the auxiliary valves will be opened according to the extent of the opening of the butter-fly valve which also controls the concentration of the mixture by reason of the interconnection of the 55 butter-fly valve and the choke cylinder.

Means may be provided for heating the primary air which is supplied to the carbureter.

The construction selected and described 60 may be greatly modified in the arrangement and manufacture of its parts and in the substitution of elements having equivalent functions and such modifications may be used for many varied purposes and still contain the 65 invention.

Having thus described my invention, what I claim as new, and desire to secure by Letters Patent, is,

1. In a carbureter the combination of a nozzle located within the air passage-way 70 and having a cone-shaped outlet and a pin opening between the end of the outlet and the interior of the nozzle and having a flaring lateral outer surface and a pin opening connecting the interior of the nozzle to the 75 lateral flaring surface of the nozzle.

2. A carbureter having a hydrocarbon liquid fuel chamber, a boss located in the bottom of the liquid fuel chamber and extending upward toward the center of the chamber, an air horn, the boss and the air horn having a passageway, a nozzle mounted on the air horn and communicating with the passageway. 80

3. In a carbureter, the combination of a 85 bowl for containing liquid hydrocarbon, an air horn for conducting air to the carbureter, the air horn having an annular channel, the bowl having a channel registering with the first-named channel, and openings opening 90 into the channels, the air horn having a passageway communicating with the channel, a nozzle communicating with the passageway in the air horn. 95

4. A carbureter having a chamber for containing liquid hydrocarbon, an air horn for conducting primary air to the carbureter and having an annular channel and a passageway connecting the annular channel with the bottom of the air horn, a nozzle secured 100 to the bottom of the horn and communicating with the passageway, the carbureter having passageways connecting the chamber for containing liquid hydrocarbon with the annular channel. 105

5. A carbureter having a chamber for containing liquid hydrocarbon, an air horn for conducting primary air to the carbureter and having an annular channel and a passageway connecting the annular channel with the bottom of the air horn, a nozzle secured to the bottom of the horn and communicating with the passageway, a boss located in the bottom of the liquid fuel chamber and extending toward the center of the liquid 110 fuel chamber, the boss having a passageway connecting with the channel in the air horn. 115

6. In a carbureter, the combination of a bowl for containing liquid hydrocarbon, a head having a mixing chamber and a tube, the tube extending through the bowl, an air horn threaded on the tube for clamping the bowl between the air horn and the head, the bowl having a boss extending around the 120 lower end of the tube and upward toward the center of the bowl, the horn having an annular channel, the boss having a passageway registering with the channel, and the horn having a passageway connecting the 125 130

- channel to the bottom of the horn, a spray nozzle secured to the bottom of the horn and communicating with the last-named passageway.
- 5 7. In a carbureter, the combination of a nozzle having a flaring lateral surface and a flaring opening in the center of the nozzle, and another opening extending laterally and angularly upward with respect to the axis of the nozzle to the flaring lateral surface of the nozzle.
8. In a carbureter, the combination of a mixing chamber, a chamber for containing liquid hydrocarbon, a protuberant part extending from the bottom of the chamber for containing liquid hydrocarbon, the protuberant part having a passageway extending therethrough and through the bottom of the chamber for containing liquid hydrocarbon, an air horn having a channel registering with the passageway through the protuberant part and a passageway formed in the end wall of the air horn and extending to the bottom of the air horn and communicating with the channel of the air horn, a spray nozzle connected to the horn and communicating with the passageway of the horn, a heating means for heating the air passing to the air horn whereby the gasoline in the end wall of the air horn and that contained in the nozzle and which passes through the nozzle is heated by the air that passes through the air horn.
9. A carbureter having a head containing a mixing chamber and a butterfly valve pivoted therein, the head having two laterally extending bosses, spring pressed valves located in the bosses for permitting the air to enter the mixing chamber, a cap plate located below the bosses, a bowl for containing liquid hydrocarbon, the head having a tubular extension extending through the bowl, the bottom of the bowl having circular protuberant parts extending into the bowl, the protuberant parts having passageways extending therethrough, a horn threaded on to the tube and having a channel registering with the passageways of the protuberant parts, the wall of the horn having a passageway communicating with the channel, a nozzle secured to the bottom of the horn and communicating with the passageway in the horn and extending into the tubular extension of the head.
- 55 10. A carbureter having a head, a butter-
- fly valve mounted in the head, a bowl for containing liquid hydrocarbon, the head having a tubular extension extending through the bowl, a cap plate for covering the bowl, the bottom of the bowl having circular protuberant parts extending into the bowl, the protuberant parts having passageways, a horn threaded on to the tubular extension for securing the head, the bowl and the horn together, the horn having a channel registering with the openings in the protuberant parts, and a passageway located in the end wall of the horn and communicating with the channel, a nozzle extending into the tubular extension and communicating with the passageway in the horn.
11. In a carbureter, the combination of a bowl for containing liquid hydrocarbon, a head having a mixing chamber, and a tubular extension extending through the bowl, an air horn threaded on the tube for clamping the bowl between the air horn and the head, the bottom of the bowl having circular protuberant parts partially surrounding the lower end of the tube and extending upward toward the center of the bowl, the protuberant parts having passageways and the air horn having a channel registering with the ends of the passageways of the protuberant parts, the end wall of the air horn having a passageway communicating with the channel, and a nozzle secured in the air horn and connected with the passageway of the air horn.
12. A carbureter having a passageway, means for conducting primary air to the passageway, a cylinder having two inner frustum surfaces, the cylinder located in the passageway, a liquid hydrocarbon nozzle having a flaring opening located in the passageway, the end of the nozzle located in the contracted portion of the cylinder, means for moving the cylinder to vary the suction of the liquid hydrocarbon through the flaring opening of the nozzle and the mixture of the primary air with the liquid hydrocarbon, the carbureter having a mixing chamber located above the nozzle, auxiliary valves located in the wall of the mixing chamber, and means for permitting one or more of the valves to be opened according to the suction produced in the chamber.

In testimony whereof, I have hereunto signed my name to this specification.

DAVID C. MEARA.
